UNITED STATES PATENT OFFICE

2,663,407

SAFETY ATTACHMENT FOR TAPE OPERATED LINE CASTING MACHINES

Paul Hilfman, Garden City, N. Y., assignor to
Mergenthaler Linotype Company, a corpora-
tion of New York

Application October 23, 1951, Serial No. 252,680

3 Claims. (Cl. 199—43)

1 This invention relates to line casting machines, such as Linotype machines of the general organization represented in U. S. Letters Patent to O. Mergenthaler, No. 436,532, wherein circulating matrices and spacebands are selectively released from storage magazines and composed in line, the composed line transferred to the face of a mold for the casting of a type bar or slug, and the matrices and spacebands then transported to an upper transfer channel where they are separated, the matrices being carried by a so-called second elevator to the distributing mechanism which returns them to their respective places of storage for further use, while the spacebands are independently returned to a separate storage magazine.

In these machines, during the casting operation the composed line is positioned in front of a mold and between a pair of vise jaws, and it is the function of the wedge-shaped spacebands to spread out or justify the line just before casting to prevent the molten metal, which is to be introduced into the mold, from squirting through the line thus positioned. Safety mechanism is provided to prevent the casting operation in the event that the composed line is too short or contains too few spacebands to be justified, and consequently, under such conditions, the type bar or slug is not produced. This failure to produce a slug may go unnoticed by the operator but an even more serious condition exists when the machine is operating under the control of an automatic unit, such as a Teletypesetter tape control unit, in which case the failure to cast will almost surely go unnoticed until some subsequent time.

Heretofore, various alarm and warning devices have been suggested to call the failure to cast to the attention of the operator, but obviously these are unsuitable for automatically operated machines.

According to the present invention, the failure of the casting mechanism to produce a slug controls the operation of a safety mechanism which stops the machine and prevents it from completing its normal cycle. In the preferred embodiment illustrated, the safety mechanism acts to obstruct the downward movement of the second elevator and thereby prevent it from reaching its lower or line receiving position. It is a characteristic feature of all Linotype machines that when the operation of the second elevator is obstructed, the driving clutch for the main cam shaft is automatically disengaged. In addition, it is a standard feature of the Teletype-

setter apparatus that when the line transfer mechanism fails to operate (which always happens when the second elevator is obstructed), all further advance of the control tape ceases. 5 The line is, therefore, hung up in the upper transfer position with the machine brought to a stop—a condition which will be at once apparent. To restart the machine, it is necessary only to back off the tape to the line which has 10 not been cast, permit the tape to recompose the line and then fill in the re-composed line with the necessary spacebands or blank spaces so that it will be able to cast.

Thus, the present invention, by interfering 15 with the normal operation of the second elevator, ingeniously utilizes existing safety features of the standard Linotype machine to achieve the desired result. The details of the present invention will be more fully described 20 in the specification which follows.

Referring to the drawings:

Fig. 1 is a left side elevation of a portion of a Linotype machine equipped with the present invention;

Fig. 2 is a front elevation of the upper transfer mechanism;

Figs. 3 and 4 are rear elevations of the present safety mechanism, illustrating different operative positions; and

Fig. 5 is a left side view of a portion of the safety device.

In the standard Linotype machine, the matrices are selectively released from one of the storage magazines 1 by the operation of a keyboard and composed in line in the order in which their characters are to appear in print. The wedge-shaped spacebands 2 are stored in a separate magazine 3 (see Fig. 2), from which they too are released by the operation of the keyboard. When a complete line has been composed, it is transported to a first elevator 4 (see Fig. 1), and the line, designated by the reference character *x* in Fig. 1, is then positioned between a pair of vise jaws (not shown) which clamp the line endwise in front of a slotted mold 5 carried by a rotatable wheel 6. In timed sequence, the mold is pressed against the line and the spacebands driven upwardly to spread out or justify the line tightly between the vise jaws. Thereafter, a metal pot 7, containing molten metal, is moved forwardly to press its discharge throat 8 against the back of the mold 5. If the line is long enough and contains a sufficient number of spacebands to justify the line, the pump plunger 9 will be permitted to descend, forcing molten

metal into the mold and against the line to produce the type bar or slug.

The operation of the pump plunger 9 is performed by a heavy tension spring 10 under the control of a cam 11 on the clutch-driven main cam shaft 12. The spring 10 is attached at its lower end to the frame of the machine and at its upper end to a lever 13, which is connected to the plunger 9 through a rock shaft 14 and a lever 15. The lever 15 is provided with a roller 16 tracking on the surface of the cam 11. The shape of the cam 11 is such as to hold the pump lever 15 in its raised or inoperative position until a cast is to be made. At that time, a very steep drop-off of the cam allows the spring 10, through the levers 13 and 15, to force the plunger downward for the cast.

Normally, however, the pump lever 15 is locked against operation by a stop (not shown), the release of which is controlled by pressure exerted against the vise jaws during justification of the line. If the line is properly justified, the stop is removed to permit the cast; on the other hand, the stop prevents the operation of the plunger if the line is not properly justified.

After the casting operation, the mold wheel 6 is rotated to slug ejecting position. Meanwhile, the first elevator 4, carrying the line of matrices and spacebands, is raised to its uppermost level where it is arrested by a fixed overhanging structure 17 of the machine frame in endwise alignment with an upper transfer channel 18. At about the same time that the first elevator 4 arrives at the upper transfer level, a second elevator 19 will have descended to a position of rest upon the top of the upper transfer channel and thus locate its horizontal toothed bar 20 endwise in line with the toothed combinations of the matrices. In its downward stroke, the second elevator pivotally operates a latch 21 which releases a transfer slide 22, actuated by a link 24, for its active stroke to the right. During this stroke, a depending finger 23 of the slide pushes the line to the right into the upper transfer channel 18 where the second elevator is waiting to receive the matrices. The spacebands, having no toothed portions, pass under the second elevator bar 20 and are supported upon rails in the transfer channel rather than by said bar. As soon as the second elevator begins its ascent to convey the matrices to the distributing mechanism, denoted generally in Fig. 1 by the reference character D, a spaceband pawl 25, carried by a lever 26, begins a stroke which carries it first to the left over the tops of the spacebands and then to the right, transferring the spacebands to their storage magazine 3.

The spaceband pawl 25, incidentally, works in conjunction with but in an opposite direction to the transfer slide 22, and the above described operations take place in two stages, the first serving to transfer the composed line from the first elevator to the upper transfer channel (during which the spaceband pawl makes only a partial stroke), and the second (when the second elevator is out of the way) allowing the spaceband pawl to make a full stroke to gather up the spacebands and restore them to the magazine 3.

The latch 21, it should be understood, is another standard safety device, the purpose of which is to prevent the operation of the upper transfer slide 22 when the second elevator does not fully descend or when the bar 20 is not properly seated in the intermediate channel 18. 75

Also, in either of these cases, it is a standard safety feature of the Linotype machine that the main driving clutch will be automatically disengaged to stop any further rotation of the main cam shaft 12.

As explained, the second elevator 19 serves to transport the composed matrices from the upper transfer channel 18 to the distributing mechanism D of the machine. The normal position of the second elevator is its upper or line delivery position as shown by the full lines in Fig. 1, but at the time the matrices are shifted from the first elevator into the upper transfer channel, the second elevator will occupy its line receiving position seated on the transfer channel. An upstanding guide post 27 facilitates the proper seating of the second elevator. The second elevator, as usual, is supported from a shaft 28 by a pivotal lever 29, and the movements of the second elevator are imparted to it, from a rotary cam 30 on the shaft 12 through a cam follower 31 and linkage arrangement 32.

The foregoing parts and their manner of operation are standard and form no part of the present invention, except insofar as they are utilized in carrying out the present invention.

From the above description of the standard Linotype machine, it can be seen that under certain circumstances the pump plunger is rendered inoperative, with the result that no slug is cast. Nevertheless, the succeeding steps in the distribution of the matrices and spacebands follow automatically, so that if the failure to cast is not observed the line will be lost and will have to be re-composed and recast when missed. Moreover, if the machine is operating automatically from a tape control unit, the loss of the slug will not ordinarily be noticed until some later time. Again, it may be that the control tape was prepared by remote control and that there is no written copy of the text from which to reset and recast the missing line, in which case the missing line will have to be sought out on the long perforated control tape.

It is the aim of the present invention to "hang up" in the first elevator 4 at the upper transfer level any composed line which has not been cast by preventing the complete descent of the second elevator 19. As before explained, transfer of the line from the first elevator will not take place until the actuation of the releasing latch 21 by the complete descent of the second elevator, and if the transfer does not take place, the clutch through which the main cam shaft 12 is driven will be automatically disengaged, preventing any further operation of the machine. Also, under these conditions, the further feed of the control tape will automatically cease as soon as the line in process of composition has been completed.

The stoppage of the machine will be quickly noticed and the cause immediately detected. The machine may then be put back into operative condition simply by backing off the tape to the line which has not been cast, permitting the tape to recompose the line and then filling in the line by hand with the necessary spacebands or blank spaces so that the length of the line when justified is sufficient to release the pump stop. Usually, the tape will have to be backed off three full lines, one for the composed line, one for the line in "waiting" position (i. e. awaiting the return of the first elevator to receive it), and finally one for the missing line.

Turning now to structure of the present safety

attachment, shown especially in Figs. 3 to 5, a stop 35 is pivoted near its lower end, as at 35^a, to a supporting bracket 36 attached to the machine frame F. Normally, the upper end of the stop is positioned in the path of travel of the second elevator supporting lever 29, as shown in Fig. 3, to prevent the complete descent thereof. However, if the casting operation has taken place, as evidenced by the downward movement of the pump actuating lever 13, the upper end of the stop will be shifted out of the path of travel of the lever 29.

The stop 35 is maintained in its normal locking position and controlled in its movement to unlocking position by a lever 37 mounted to turn about the same pivot 35^a. The lower end of the lever 37 engages the pump actuating lever 13, and the contour of the engaging edge thereof includes a depression 37^a and an elevation or raised portion 37^b. The upper end of the lever 37 carries an adjustable screw 38 which connects it with the stop 35.

The stop 35 carries a horizontally disposed pivoted catch member 39 presenting at one end a hook 39^a and carrying at the other end a vertical set screw 40 which acts as a trip. A small tension spring 41, anchored to the bracket 36 below the catch member 39, is connected to a pin 42 protruding from the hook end of the said member. The spring 41 normally keeps the pin 42 in banking contact with the top edge of the bracket 36, and, in addition, acts to maintain the stop 35 in the obstructing position shown in Fig. 3. In this position of the stop, the pump actuating lever 13 is located in the depression 37^a of the lever 37.

During casting, the pump actuating lever 13 moves vertically downward, as shown in Fig. 4, engaging the high portion 37^b of the lever 37 and thereby pivoting the stop 35 out of the vertical path of travel of the second elevator lever 29. As the stop is thus pivoted out of the way, the hook 39^a of the catch member 39 engages behind the upper edge of the mounted side of the bracket 36 and thus temporarily holds the stop out of operative or obstructing position.

As the second elevator 29 reaches its lowermost position (see dotted line in Fig. 4), it comes into contact with the set screw 40, rocking the catch member 39 about its pivot to disengage it from the bracket 36, and permitting the spring 41 to move the stop 35 against the side of the lever 29. The manner of release of the stop 35 is illustrated by the dotted lines in Fig. 4. As soon as the lever 29 rises to move the second elevator to the distributor D, the stop 35 is completely returned by the spring 41 to its normal operative position, as indicated in Fig. 3. Such is the normal operation of the parts.

If the casting operation does not take place, the pump actuating lever 13 fails to remove the stop 35 from the path of the second elevator lever 29 and hence the second elevator is stopped in the position indicated by the dotted lines in Fig. 1, with the result that the latch 21 locks the upper transfer slide 22 against operation and causes the driving clutch for the main cam shaft 12 to be automatically disengaged and thus preventing any further machine operations.

The set screw 40 may, of course, be adjusted to regulate the time of release of the catch member 39, and the set screw 38 may be adjusted to position the upper end of the stop 35 in proper relation to the path of travel of the second elevator lever 29.

The invention has been shown and described in preferred form and by way of example, but obviously many variations and modifications may be made therein and in its mode of application which will still be comprised within its spirit. For example, the present safety device could be employed in conjunction with some warning or signal device for calling attention to the fact that the operation of the machine has been arrested. Again, the device could be employed in conjunction with a control switch for arresting the tape feed of the automatic control unit instantly, instead of at the completion of the line in composition, as is now the case.

It is to be understood, therefore, that the invention is not to be limited to any specific form or embodiment, except insofar as such limitations are specified in the appended claims.

25 What is claimed is:

1. In a line casting machine equipped with a second elevator and a pump plunger, the combination therewith of a stop member normally occupying an active position to prevent the complete downward movement of the second elevator, and means actuated by the casting movement of the pump plunger to move the stop member to an inactive position to permit the complete downward movement of the second elevator.

35 2. In a line casting machine equipped with a second elevator and a pump plunger, the combination therewith of a stop member normally occupying an active position to prevent the complete downward movement of the second elevator, means actuated by the casting movement of the pump plunger to move the stop member to an inactive position to permit the complete downward movement of the second elevator, and automatic means for restoring the stop member to its active position after the casting operation.

3. In a line casting machine equipped with a second elevator and a pump plunger, the combination therewith of a stop member normally occupying an active position to prevent the complete downward movement of the second elevator, means actuated by the casting movement of the pump plunger to move the stop member to an inactive position to permit the complete downward movement of the second elevator, a latch for locking the stop member temporarily in its inactive position, and trip means actuated by the complete downward movement of the second elevator for releasing said latch to permit the return of the stop member to its normal active position.
